UNITED STATES PATENT OFFICE

103,167

DESIGN FOR A PITCHER

Anne Swainson, Chicago, Ill., assignor to Montgomery Ward & Co., Incorporated, Chicago, Ill., a corporation of Illinois

Application June 29, 1936, Serial No. 63,555

Term of patent 7 years

To all whom it may concern:

Be it known that I, Anne Swainson, a citizen of the United States, residing at Chicago, in the county of Cook and State of Illinois, have invented a new, original, and ornamental Design for a Pitcher, of which the following is a specification, reference being had to the accompanying drawing, forming a part thereof.

In the drawing:

Fig. 1 is a side elevation of a pitcher showing my new design;

Fig. 2 is a top plan view thereof; and

Fig. 3 is also a side elevation of the pitcher viewing the same at right angles to the viewpoint of Fig. 1.

I claim:

The ornamental design for a pitcher, as shown.

ANNE SWAINSON.
